Charles L. Wright
ATTORNEY

UNITED STATES PATENT OFFICE.

FRANK A. PHILLIPPI, OF POTTSTOWN, PENNSYLVANIA.

WATER COOLER.

Application filed December 16, 1922. Serial No. 607,271.

This invention relates to improvements in water coolers as used in connection with circulating systems and has as one of its objects to provide a cooler, or preferably a series of the same, so arranged within a tank or refrigerating chamber as to present its entire exterior to the effects of the refrigerant, as ice packed in the tank.

Another purpose is to produce a cooler unit made in sections and so designed as to avoid machine work except for the water inlet and outlet, these sections permitting ready separation at any desired time.

A further aim is in the provision of means for washing the interior of the cooler units in a thorough manner, removal of sediment and the like, without separation of the sections or removal of the same from the tank.

A still further object is to combine with one or more of the water inlet pipes a regulating valve whereby the pressure may be reduced as required.

These and other like aims, objects and purposes, such as economy in construction, neatness of appearance, compactness and general utility, are accomplished by the novel construction, combination and arrangement of parts hereinafter described and shown in the accompanying drawing, constituting a material part of this disclosure, and in which:—

Figure 1 is a fragmentary sectional view of a conventional form of ice tank, showing two of the cooler units therein, one being in section and the other in side elevation.

Figure 2 is a bottom plan view of the upper element of the cooler.

Figure 3 is a similar view of the lower element.

Figure 4 is a longitudinal sectional view of the pressure reducing valve, showing its connection.

Figure 5 is a fragmentary sectional view, showing the application of a central section to the cooler units.

In the drawing the numeral 10 designates the floor or bottom wall of a tank and 11 the end and side walls thereof, over which a removable cover 12 is disposed, the tank being filled with broken ice as at 13.

The cooler units are composed usually of two main sections 14 and 15, the same being circular in cross section, generally conical in shape and provided with integral heads 16 and 17 joined by smooth curves as shown, the entire interior surfaces being lined with a vitreous white enamel.

The lower member 15 is formed with an upstanding annular flange 18 thus providing a recess into which enters the corresponding abutting end 19 of the upper member, a packing ring 20 being interposed to make a tight joint.

Extending outward from these members, adjacent their juncture, are rigid lugs 21 and 22, the latter having recesses 23, and engaging the lugs 21 are eyes 24 formed with bolts 25 capable of entering the recesses 23 and being clamped thereover by nuts 26.

Thus the sections may be quickly clamped securely together or separated at will and it will be apparent that the number of these paired lugs may vary according to the size of the cooler elements.

It will be further apparent that a central cylindrical section 27 may be interposed in order to lengthen the operative length of the cooler in a manner indicated in Fig. 5, the ends of the intermediate section being suited to engagement with the adjacent ends of the cooler members as before described.

These cooler units may rest directly on the flooring 10 or preferably upon plates 28.

At points adjacent the bottoms of the lower elements 15 screw-threaded openings, serving as washout, are made through the wall and supplied with plugs 29, readily removable when cleansing the interior.

Formed on the outer surface of the end element 16 of upper member 14 of the cooler units are raised bosses 30 and 31 having their side faces drilled and tapped, as at 32 and 33 to receive the corresponding ends of outlet and inlet pipes 34 and 35, the former passing out through the side of the tank and a flange 36, the inlet entering in a similar manner.

The lateral openings in the bosses intersect longitudinal openings 37 and 38, in the manner of T fittings, the outer openings

being fitted with plugs 39 and 40, the inner opening in the boss 30 communicating directly with the tank as shown in Fig. 1.

Engaged in the opening 37 of the mating 5 boss 31 is a tube 41 extending far down into the lower element 15 and fixed in the body of a reducing valve 42.

Said valve body contains a screw-threaded opening 43 in its lower end in which is an 10 adjustable plug 44 having a bore 45 in its upper end, the lower end being provided with an extending rim 46 by which it may be turned to advance the plug up or down in the head 42.

15 A plurality of relatively small transverse openings 47 intersect the reduced bore 48, above which is a shoulder or valve seat 49 adapted to have the sphere or ball 50 make contact, closing the opening 51 at the end 20 of the tube 41.

A plunger 52 supportingly receives the ball 50, the plunger and ball being freely movable and carried at the end of a stem 53, encircled by a compression spring 54 located 25 in the bore 45 of the plug.

Thus more or less pressure can be applied to the ball, which resisting the force of the incoming stream of water, reduces the same to the required pressure.

30 It will be obvious that only one of the reducing valves need be used and that preferably on the first inlet tube, but that if a separate head be used in each cooler unit, the water will be kept in a state of agitation 35 when in operation.

Where several units are used they will be interconnected as indicated, unions being used in the pipes so that substitution can be easily effected, without disturbing the 40 assemblage of the cooler units, any number of which can be used in consecutive relation.

45 Due to the relative large surface of the coolers exposed to the ice, the water passing through the pipes is quickly and effectively cooled at a minimum of expense, and as has been seen, the cooler units can be cleaned in an expeditious and efficient manner.

Although I have described my improvements with considerable detail and with respect to certain particular forms of my invention, I do not desire to be limited to such details since many changes and modifications may well be made without departing from the spirit and scope of my invention in its 55 broadest aspect.

Having thus described my invention, what I claim as new and desire to secure by Letters Patent, is:—

1. A cooler unit comprising two substantially equal, hollow conical elements having respectively tenon and socket interengaging surfaces at their base edges, paired lugs extending laterally from their adjacent outstanding edges, one of each pair of lugs being forked and the other cylindrical, eye

bolts engaging circumferentially around the cylindrical lugs and adjustable within forks of the mating lug, means for the inlet and outlet of water to said units, and means for discharging the contents of said unit formed 70 in one of said sections.

2. A cooler unit comprising two equal, hollow conical elements having interengaging surfaces at their base edges, removable clamping means for sections, said unit being 75 disposed in a vertical plane, means for the entrance and exit of water to the upper of said sections, a tube engaging the inlet means to extend into the lower of said sections, a hollow head on the inner end of said tube, 80 said head having a plurality of lateral openings, a spherical valve seat in said head, a manually operable screw engaged in said head below the seat, said screw having an axial recess, a spring in the recess, a plunger 85 resting on the spring, a ball valve seated on said plunger adapted to close against the valve seat and removable means in said lower section for discharging the contents of said unit. 90

3. A cooler unit comprising two equal, hollow conical elements having interengaging surfaces at their contacting base edges, a packing ring interposed therebetween, forked radial lugs on one of said elements 95 near the base thereof, cylindrical projections on the other element registering with said lugs, said projections having notches in their outer surfaces, bolts having eyes encircling said projections engaging in the mentioned notches, the bodies of said bolts passing between the forks of said lugs, nuts on said bolts for rigidly clamping said sections together, inlet and outlet means on the upper of said sections, a drain in the lower section, 100 a tube extending from said inlet means into the lower portion of the lower element, a cylindrical head fixed on said tube to extend downwardly, said head having a plurality of radial openings in its upper end, a spherical valve controlling the passage through the mentioned openings, a spring normally tending to press said valve against its seat said seat being above the openings, and means for manually adjusting the action of said 105 spring. 110

4. A cooler unit comprising two equal, hollow conical elements having interengaging surfaces at their base edges, a packing ring interposed therebetween, a pair of bosses on the outer end of said upper element, said bosses having inreaching and intersecting lateral openings, inlet and outlet pipes fixed in the mentioned lateral openings, a tube engaged in the bore of the boss containing the inlet pipe, said tube extending past the joint between said sections, an adjustable reducing valve in the end of said tube and manually operable means for adjusting said valve. 115 120 125 130

5. A cooler comprising in combination with an ice container, of a series of hollow conical units formed of substantially equal sections disposed in said container, releasable means for clamping said sections in rigid engagement, inlet and outlet openings on one of each of said sections, and connec-

tions from the inlet openings of one section extending to the opposite ends of the other sections whereby a liquid may be progressively passed throughout the entire series. 10

In testimony whereof I have signed my name to this application.

FRANK A. PHILLIPPI.
